(57) **CLAIM**

The ornamental design for a sight for a pistol as shown and described.

DESCRIPTION

FIG. 1 is a front, top and right side perspective view of a sight for a pistol showing my new design;

FIG. 2 is a top, rear and left side perspective view of the design shown in FIG. 1;

FIG. 3 is a bottom and front perspective view of the design shown in FIG. 1; and,

FIG. 4 is a left side, top and rear perspective view of the design shown in FIG. 1.

Any color shown on the claimed design forms no part thereof.

1 Claim, 4 Drawing Sheets
